UNITED STATES PATENT OFFICE

111,575

DESIGN FOR A DISPLAY CABINET

Raoul J. Vezina, Springfield, Mass.

Application May 7, 1938, Serial No. 77,066

Term of patent 14 years

To all whom it may concern:

Be it known that I, Raoul J. Vezina, a citizen of the United States of America, residing at Springfield, in the county of Hampden and State of Massachusetts, have invented a new, original, and ornamental Design for a Display Cabinet, of which the following is a specification, reference being had to the accompanying drawing, forming part thereof.

Fig. 1 is a perspective view of the display cabinet, showing my design, and Fig. 2 is a top plan view of the same, broken away at one end.

I claim:

The ornamental design for a display cabinet, substantially as shown.

RAOUL J. VEZINA.
